United States Patent Office

Des. 216,739
Patented Mar. 3, 1970

216,739

TRASH CONTAINER

William Jackson Marsh, Garden Grove, Calif., assignor to Plasworld, Inc., a corporation of California

Filed Apr. 21, 1969, Ser. No. 16,828

Term of patent 14 years

Int. Cl. D7—99

U.S. Cl. D49—35

FIG. 1.

FIG. 2

FIG. 3.

FIG. 1 is a front perspective view of a trash container, showing my new design;

FIG. 2 is a rear elevation thereof; and

FIG. 3 is a side elevation thereof.

I claim:

The ornamental design for a trash container, as shown.
